UNITED STATES PATENT OFFICE.

KARL VÖLLER, OF DUSSELDORF, GERMANY.

AIMING APPARATUS FOR GUNS.

979,232.

Specification of Letters Patent. Patented Dec. 20, 1910.

Application filed August 15, 1910. Serial No. 577,224.

To all whom it may concern.

Be it known that I, KARL VÖLLER, engineer, a subject of the German Emperor, residing at 17 Filicherstrasse, Dusseldorf, 5 Germany, have invented certain new and useful Improvements in Aiming Apparatus for Guns; and I do hereby declare the following to be a full, clear, and exact description of the invention, such as will enable 10 others skilled in the art to which it appertains to make and use the same.

This invention relates to an aiming apparatus which purposed to solve the problem of automatically compensating the lateral 15 deviation of the shot arising from the rifling at different elevations of the barrel.

The sighting device consisting of a horizon 20 and a muzzle sight, or of a telescope, is mounted to rotate on the cradle or the barrel around a horizontal pin at right angles to the axis of the barrel; at the same time it is rotatable about a vertical pin. It is provided with guiding rollers which coöperate with a guiding curve so formed that by its 25 movement the sighting device is turned simultaneously about the horizontal pin and the vertical pin. The guiding curve is so constructed that it turns the sighting device in every position through a lateral angle 30 about the vertical pin, which angle corresponds with the deviation of the shot at the angle of elevation which is formed between the sighting line and the axis of the barrel in the rotation about the horizontal pin. 35 The guiding curve is preferably of spiral form and carried by a disk adapted to rotate about a horizontal axis. In this manner a very compact construction is obtained.

The invention is illustrated by way of 40 example in the accompanying drawing.

Figure 1 is a side elevation of the sighting device and Fig. 2 is a rear elevation thereof.

The carrier *c* is screwed to the cradle *a* 45 in which the gun barrel *b* recoils when the gun is fired. On a horizontal pin *d* mounted in this carrier turns an intermediate piece *e* carrying a vertical pin *f*. On the latter rotates the sight carrier *g* whereon is mounted 50 the sighting device, in this case a horizon *h* and a muzzle sight *i* and a telescope *k*. At its rear end the carrier *g* is provided on its under surface with an undercut guide rail *m* curved to an arc struck from the axis of the

pin *f*. In this rail engages a slide *n* which 55 is adjustable therein by means of an automatically locking operating mechanism, such as a screw and nut, which can be turned by a hand wheel *o*.

In an arm of the carrier *c* is journaled a 60 shaft *p* parallel to the axis of the pin *d*; this shaft can be rotated through a worm drive or the like by means of the hand wheel *g*. A segmental disk *r* having a spirally 65 formed groove *s* is fixed to the free end of the shaft *p*; it is not plain but is curved at right angles to its axis of rotation, particularly at its periphery (see particularly Fig. 2). The slide *n* is forked over the disk *r* 70 and carries a roller *t* which engages in the groove *s*. It also has two rollers *u* situated one on each side of the disk and engaging with the periphery thereof for lateral guiding.

The operation is as follows:—When the 75 gun is being aimed the hand wheel *g* is turned to rotate the shaft *p* and with it the disk *r*. Owing to the spiral form of the groove *s* the rear end of the sight carrier *g* is raised or lowered through the slide *n* 80 according to the direction of rotation of the shaft *p*. In this manner the angle between the sighting line and the axis of the barrel is changed and this angle can be read off each time by a suitable device of known kind. 85 During the turning movement of the disk *r* the rear end of the sight carrier *g*, in consequence of the curved construction of the disk, is simultaneously deflected laterally about the pin *f* by the rollers *u*. The position of the carrier *g* is thus varied in horizontal direction correspondingly with variations of the angle between the sighting line 90 and the axis of the barrel. The curvature on the surface of the disk *r* is such that the lateral deviation of the shot is exactly compensated for at each elevation of the barrel by the lateral deflection of the sighting line. 95

The operating mechanism between the slide *n* and the sight carrier *g* is for the purpose of making a lateral correction of the line of sight independent of the movement due to the disk *r*.

In the example shown the part which effects the simultaneous vertical and horizontal movements of the line of sight relatively to the axis of the barrel takes the form of a rotary disk. This part, however 105

may equally well be constructed in various ways.

Having thus described my invention and the best means I know of carrying the same 5 into practical effect, I claim:—

1. In an aiming apparatus for guns, the combination with a sighting device, a carrier for supporting the latter having a horizontal pivot bearing and a vertical pivot bearing, a bifurcated element depending from said carrier at one end thereof, a rotary disk having cam surfaces at right angles to each other for engaging said element for raising and lowering the carrier 10 on its horizontal bearing and for shifting it laterally on its vertical bearing.

2. In an aiming apparatus for guns, the combination with a sighting device, a carrier for supporting the latter having a horizontal pivot bearing and a vertical pivot bearing, a bifurcated element depending from said carrier at one end thereof, a rotary disk of cam formation engaging said element for raising and lowering the carrier 15 on its horizontal bearing, said disk being

curved at right angles to its axis of rotation for moving said carrier on its vertical bearing.

3. In an aiming apparatus for guns, the combination with a sighting device, a carrier for supporting the latter having a horizontal pivot bearing and a vertical pivot bearing, a muzzle sight at one end of the carrier, a sighting device mounted on the other end of the carrier, a bifurcated element depending from one end of the carrier, a rotary cam disk fitted between the members of said bifurcated element, and means for rotating said disk, which rotation is designed to effect the raising or lowering of the carrier and the lateral shifting thereof, said disk being curved at right angles to its axis of rotation. 30 35

In testimony whereof, I have signed this specification in the presence of two subscribing witnesses. 40 45
